UNITED STATES PATENT OFFICE

JAMES L. SHANNON, OF LONGMEADOW, MASSACHUSETTS, ASSIGNOR, BY MESNE ASSIGNMENTS, TO FRENCH BATTERY COMPANY, OF MADISON, WISCONSIN, A CORPORATION OF WISCONSIN

ELECTRIC FLASH LIGHT

Application filed March 11, 1930. Serial No. 434,942.

This invention relates to improvements in electric flashlights of the type in which dry cells are placed in an enclosing tubular shaped casing; one end of the casing having a detachable closure member for inserting and removing the dry cells. The opposite end of this casing is provided with a cap or head piece in which is removably inserted the reflector that is provided with bulb sockets. Secured in the sockets are a plurality of electric bulbs which are in electric circuit when the reflector is placed in the cap piece. Suitable switches, not shown, are provided for closing the circuits to the different bulbs. The outer end of the cap piece is formed with a threaded portion that receives the bezel for securing the lens in place and for attaching the reflector to the cap piece.

An object of the present invention is to provide means for accurately positioning the bulbs in the cap piece with respect to the different circuits, so that when the reflector is inserted, the lamp terminals in their sockets will engage the contact strips and close the electric circuit.

A further object is to provide means for preventing the displacement of the reflector, after insertion in the cap piece.

The invention comprises a removable cylindrically shaped cage-like member, one edge of which is formed with a struck-up or indented portion that is designed to enter a recess in the upper end of the battery enclosing casing for the purpose of retaining it in place and for aligning the lamp terminals.

This cage member is formed with cutout openings to receive the ends of the electric contact strips, the bottom or base portion of this member is formed with a rectangular shaped opening to receive a correspondingly shaped member on the reflector, whereby when the rectangular shaped member enters the rectangular shaped opening of the cage-like member, the reflector cannot be axially rotated out of its assembled position, also the lamp terminals in the sockets are brought directly into contact with the circuit strips, as will be described. The cap piece is formed with an enlarged portion for receiving the cage-like or barrel shaped member in order

to permit its easy insertion and removal, if necessary. Means is provided for insulating the reflector from the cap member.

Referring to the drawing:

Fig. 1 is a partial longitudinal sectional view considered in a plane passing thru the axis of the enclosing casing illustrating the casing and cap member in section and the reflector with the lamp terminals engaging the contact strips, also, the rectangular shaped portion on the reflector entering a correspondingly shaped opening in the removable cage member.

Fig. 2 is a transverse sectional view on the line 2—2 of Fig. 1 looking in the direction of the arrows showing the struck-up portion of the cage or barrel member entering a depression or slot in the end of the battery enclosing casing, also showing the three contact strips and the battery terminal.

Fig. 3 is a transverse sectional view on the line 3—3 of Fig. 1 looking in the direction of the arrows showing the rectangular shaped part on the reflector in the correspondingly shaped part in the cage or barrel member, the three contact strips, and

Fig. 4 is a detail perspective view of the cage or barrel member removed from the casing.

Referring to the drawing in detail:

1 designates the enclosing casing formed, as shown, of insulating material, 2 the cap or head member having the portion 3 which is secured to the casing 1 in any suitable way, as for example, with hollow rivets. 3' designates an enlarged portion of the cap piece 2. Located within the cap piece 2 is the reflector member 4 which carries the three electric bulbs, 5, 6, and 7, indicated in dotted lines, that are threaded into the sockets 8, 9 and 10. The cap 2 carries the lens 11 at its outer end which is secured in place by means of the bezel 12 having threaded connection with the threads 13 of the cap. The bezel also serves to secure the reflector in place. 14 is a ring of insulation which projects above the outer end of the cap 2 for insulating the reflector from the cap, as shown at 14'; 15 is a wire ring located in the bead portion 16 for preventing the ring of insulation being forced into the

cap when the bezel 12 is tightened. One of the battery cells is indicated at 17, the terminal 18 of which engage the contact strip 19 that closes the circuit with the reflector 4, as indicated at 20. The other circuit strips are indicated at 19¹, 19² and 19³.

Referring to Fig. 4, 21 indicates as a whole a hollow cage-like or barrel member which is located in the enlarged portion 3' of the cap 2. 10 This member is formed with a struck-up or indented portion 22 in the rim 23. This struck-up portion is designed to enter the notch 24 that is formed in the upper end of the casing 1, as clearly shown in the Figs. 1 and 15 2. When the cage member is inserted, it is therefore accurately positioned against displacement on the casing 1. The side of the cage member 21 is formed with the three cut-out openings 25, 26, and 27, for receiving the 20 contact strips, see Fig. 1. The top 28 of this member is formed with the square or rectangular shaped opening 29. The purpose of this shaped opening is to receive the rectangular shaped part 30 that is fixedly secured to the 25 socket 9 of the reflector, whereby when this rectangular shaped portion enters the opening 29, it prevents the reflector and all of the bulb terminals from becoming displaced against rotation with reference to the contact strips, since the cage-member is secured to the casing against rotation with the recess 24 and projection 22.

It will be seen from this description that I have provided an electric flashlight construction in which a removable cage-like member is employed and is formed with an angular shaped opening for receiving a correspondingly shaped co-operating part on the reflector or for positioning the reflector and the terminals of the bulbs, also with means co-operating between the cage-like member and the cell receiving casing for preventing the cage from being turned relative to the casing, whereby both the reflector and cage are retained in place, the construction and arrangement of which parts accurately aligns the lamp terminals with the several circuit strips. One of the advantages of the present construction resides in the elimination of a disk of insulation that is employed in a great many different types of flashlights.

The ring of insulation shown at 14 is located at a point that is substantially removed 55 from the contact terminals and by reason of its edge projecting above the end of the cap, as shown at 14', the reflector is thoroughly insulated from the cap piece. Not only does the rectangular opening 29 and the rectangular part 30 provide for the accurate positioning of the lamp terminals, it also prevents the reflector from being rotated when the bezel member 12 is tightened.

It is, of course, obvious that the shape of the 60 opening 29 and part 30 may be changed, as

triangular, in order to accomplish the same purpose.

What I claim is:

1. In a flashlight construction, in combination with a battery enclosing casing, a cap 70 for the casing, a cage member connected to the casing and having co-operating means between the casing and cage member to prevent rotation of the cage member, after insertion, a reflector, lamp sockets thereon, a square 75 part on the central lamp socket of the reflector engaging a square central opening in the cage member for preventing annular movement of the reflector relative to the cage member, contact strips for the lamps, the construction and arrangement being such that when the reflector is inserted in the cap, it is accurately positioned to bring the lamp terminals in contact with the circuit strips, means for attaching the reflector to the cap, 80 and sleeve means for insulating the cap from the reflector.

2. As an article of manufacture, a cage-like member for the purpose described, having a rim portion with an offset part, the sides 90 of the cage member having openings therein to receive circuit strips and the end of the cage member being formed with an angular shaped opening.

3. In an electric flashlight in combination with battery enclosing casing one end of which is formed with a notch, a cap member, a reflector, lamps thereon, a cage member having a part engaging the notch for retaining it in place on the casing and openings for receiving circuit strips, a portion of said member having an angular shaped opening for receiving a correspondingly shaped portion on the reflector of the flashlight, whereby when said portion on the reflector enters the opening in the base, the lamp terminals will engage the circuit strips and prevent the reflector from movement relative to the cap member.

4. A flashlight construction having in combination with the casing member of a cage-like member engaging the casing member, a lamp carrying reflector, co-operating means between the casing and the cage member for retaining the same against displacement, relative to the casing, an end of the cage-like member having an angular shaped opening to receive a correspondingly shaped member on the reflector, whereby when the reflector is inserted, the lamp terminals are accurately positioned, as described, and the reflector is retained against movement.

JAMES L. SHANNON.
